GAS-BURNING HEATER AND AIR
CIRCULATING FAN

Franklin E. Modlin, Fort Worth, Tex., assignor of
one-third to George A. Brightwell and one-
third to W. K. Martin, both of Fort Worth,
Tex.

Application November 8, 1944, Serial No. 562,453

8 Claims. (Cl. 126—110)

1

This invention relates to heaters and heat circulating means, and in such connection it relates more particularly to a device for generating heat by the use of natural gas, artificial gas, kerosene, gasoline or the like.

The present invention is a continuation in part of application for Letters Patent for Heater and Heat Circulating Means, filed August 14, 1941, Ser. No. 406,801, but which became abandoned.

The principal object of the invention is to produce a heater designed to provide combustion of the above products in such a manner that the maximum of heat may be derived therefrom, and further that the heated air may be circulated through a room or confined space for heating purposes.

Another object of the invention is to simplify its construction by providing a more restricted space for combustion of the gases, and is provided with a noiseless fan for quiet operation. The fan operates to pull the air into the heater where it is heated and to return the air to the heater by circulation for re-heating, the air being drawn directly through the flame of the burner, expelled by force of the fan into the room and the air drawn in again at the bottom of the heater, causing a constant circulation. The combustion arrangement is such that the utmost heat is obtained and more b. t. u.'s produced with a less amount of gas.

In the accompanying drawings is illustrated a preferred means of carrying out the above objects, the drawing showing the design, construction and mode of operation of the heater, and in the drawing:

Figure 1 is a vertical sectional view in elevation of a heater embodying the invention;

Figure 2 is a plan view of the burner, partly broken away, and removed from the heater;

Figure 3 is a plan view of the fan for causing the air to be circulated through the heater and through the room.

In carrying out the invention there is provided a housing 1, mounted on the supporting legs 2, the legs being sufficiently spaced to permit the air to enter at the bottom of the heater. The legs are bolted as at 3 to the housing which is open at the bottom as shown. The top of the housing 1 is also open and has a top plate 4, this plate being spaced from the housing by the supports 5 so as to permit the hot air to escape from the top of the heater.

A burner 6 of the spider type to permit the air to pass in between the fingers 7 has a central hub 8. The burner is supported on angle irons

2

9, bolted to the inner wall of the housing. The burner includes a neck piece 10 for entrance of gas at the intake member 11 and is flared as shown for entrance also of air for the purpose of combustion of the gases.

Inside the housing is a conical shaped skirt 12, also open at the top, the lower portion of the skirt being supported by the angle irons 9, these members being passed through openings 13 in the skirt, with the neck of the burner at 10 passing through an opening 14 in the wall of the housing 1.

An electric motor for generating air circulation and shown at 15 is mounted near the lower end of the housing and is supported on a strap 16, bolted to the walls of the housing through means of the lugs 17.

The motor includes a shaft 18, connected to a fan, see also Figure 3, the upper end of the shaft being provided with bearings 19. Between the plate 4 and the top of the housing and the upper end of the skirt is a hub 20 provided with curved fingers 21 and on these fingers are secured by bolts as shown the fan blades 22. The peculiar form of the fan thus makes for quieter operation of the heater when in operation.

A tubular shafting 23 has its lower end seated in the opening 24 in the hub 8 and protects the shaft, and also strengthens its position.

Arranged on the tubular shafting just above the burner is a baffle 25 which ensures a retarding of the flow of gases so that the gases will become thoroughly mixed with air, where the gases then flow to the top of the reduced portion of the skirt and are thoroughly mixed before leaving the burner through the openings between the supports 5.

In the burner neck, the fingers thereof 7 and the hub 8 are small openings for escape of gases into the heater, indicated at 27.

In the operation of the heater, the air in the room or other space to be heated is drawn in at the bottom of the housing and between the legs 2, and passes in between the fingers of the spider form of burner, thus passing through the flame area of the burner. The flame projecting against the baffle 25 retards the passage of the heat generated by the gas sufficiently to momentarily confine the heated air and fumes within the space C, where complete combustion takes place. The heated air then flows around and over the edges of the baffle 25 and thence upwardly and within the upper part of the skirt and thence outwardly as described. In practical demonstration the heater thus provides a con-

stant circulation of the air within the entire room, drawing in the cooler air at the bottom of the housing and continuously circulating the same through the room. The heater is regulated by the extent or amount of gas allowed to be consumed by controlling the flame of the burner.

While the disclosure presents a practical working embodiment of a heater constructed in accordance with the invention, it is to be understood that the invention is susceptible of modifications, alterations, and changes, in keeping with the inventive thought and which may be said to come within the scope and meaning of the appended claims.

What is claimed is:

1. A heater of the character described comprising an upright cylindrical outer casing open at top and bottom to permit free circulation therethrough, an upwardly and inwardly tapering conical skirt member concentrically mounted within said casing but spaced therefrom, a plate spaced above said casing and supported thereon, a burner mounted within the lower portion of said conical skirt member, an upwardly and outwardly inclined conical baffle member supported within said skirt above said burner in spaced relation thereto, and with its periphery spaced from the wall of the skirt member, a centrifugal fan housed in the space between the top of the casing and said plate, a fan motor mounted below the burner, and a fan shaft driven by said motor, said shaft being concentric with the skirt member and extending through the centers of said burner and of said conical baffle, whereby hot gases from the burner are deflected away from said shaft.

2. A heater of the character described comprising an upright cylindrical outer casing open at top and bottom to permit free circulation therethrough, an upwardly and inwardly tapering conical skirt member concentrically mounted within said casing but spaced therefrom, a plate spaced above said casing and supported thereon, a burner mounted within the lower portion of said conical skirt member, an upwardly and outwardly inclined conical baffle member supported within said skirt above said burner in spaced relation thereto, and with its periphery spaced from the wall of the skirt member, a centrifugal fan housed in the space between the top of the casing and said plate, the blades, of said fan extending laterally beyond the limits of the reduced upper end of said skirt member, a fan motor mounted below the burner, and a fan shaft driven by said motor, said shaft being concentric with the skirt member and extending through the centers of said burner and of said conical baffle, whereby hot gases from the burner are deflected away from said shaft.

3. A heater of the character described comprising an upright cylindrical outer casing open at top and bottom to permit free circulation therethrough, an upwardly and inwardly tapering conical skirt member concentrically mounted within said casing but spaced therefrom, a plate spaced above said casing and supported thereon, a burner mounted within the lower portion of said conical skirt member, an upwardly and outwardly inclined conical baffle member supported within said skirt above said burner in spaced relation thereto, and with its periphery spaced from the wall of the skirt member, a centrifugal fan housed in the space between the top of the casing and said plate, said fan having a drive shaft concentric with said casing and extending

the full length of said skirt and through the centers of said conical baffle member and of said burner, whereby hot gases from the burner are deflected away from said shaft by said baffle.

5. A heater of the character described comprising an upright cylindrical outer casing open at top and bottom to permit free circulation therethrough, an upwardly and inwardly tapering conical skirt member concentrically mounted within said casing but spaced therefrom, a plate spaced above said casing and supported thereon, a burner mounted within the lower portion of said conical skirt member, an upwardly and outwardly inclined conical baffle member supported within said skirt above said burner in spaced relation thereto, and with its periphery spaced from the wall of the skirt member, a centrifugal fan housed in the space between the top of the casing and said plate, said fan having a drive shaft concentric with said casing, and a tubular housing for said shaft, supported by said burner and supporting the conical baffle.

20. 5. A heater of the character described comprising an upright cylindrical outer casing open at top and bottom to permit free circulation therethrough, an upwardly and inwardly tapering conical skirt member concentrically mounted within said casing but spaced therefrom, a plate spaced above said casing and supported thereon, a burner mounted within the lower portion of said conical skirt member, an upwardly and outwardly inclined conical baffle member supported within said skirt above said burner in spaced relation thereto, and with its periphery spaced from the wall of the skirt member, a centrifugal fan housed in the space between the top of the casing and said plate, said fan having a drive shaft concentric with said casing, and a tubular housing for said shaft, supported by said burner and supporting the conical baffle.

25. 40. 6. A heater of the character described comprising a housing open at the top and bottom and mounted upon spaced legs, a plate spaced from the top of the housing and supported by spaced members which connect the plate with the upper end of the housing, a fan arranged in the space between the plate and the upper end of the housing, an electric motor having a shaft extending axially through the housing and connected with the fan to rotate the same, a skirt member supported within the housing, concentric with said housing, communicating with said fan, and open at the top and bottom, a burner enclosed in the lower end of the skirt member, a baffle within said skirt located above the burner to retard the flow of gasses momentarily in bringing about complete combustion, and a tubular housing for the motor shaft supported upon the burner and supporting the baffle.

65. 7. A heater as set forth in claim 6 wherein the baffle has its edges spaced from the walls of the skirt member to permit gases to flow to the upper end of said skirt member, said baffle being mounted just above said burner.

70. 8. A room heater of the character described comprising a housing open at the top and bottom for passage of gases and air therethrough, an upwardly and inwardly tapering conical skirt member within the housing open at top and bottom, a burner inside the conical skirt member for generating heat, means including a fan,

for circulating the heat through the heater and room and for returning the air again to the heater, said fan having a shaft extending axially through the skirt member, an electric motor for revolving the fan, and an upwardly and outwardly inclined conical baffle within said skirt member surrounding said shaft and supported upon the burner, said baffle serving to momentarily retard the gases and air in bringing about complete combustion and to direct the hot gases away from said shaft, the baffle being spaced from the interior of the skirt to permit passage of the gases to the top of the heater, both said burner and said baffle being enclosed in the enlarged lower end of the conical skirt member. 5
